Inventor:
Arthur Haddock,
by W. Griggs Atty

UNITED STATES PATENT OFFICE.

ARTHUR HADDOCK, OF EAST ORANGE, NEW JERSEY, ASSIGNOR TO WESTERN ELECTRIC COMPANY, INCORPORATED, OF NEW YORK, N. Y., A CORPORATION OF NEW YORK.

RADIOTRANSMITTER.

Application filed September 28, 1923. Serial No. 665,265.

To all whom it may concern:

Be it known that I, ARTHUR HADDOCK, a citizen of the United States of America, residing at East Orange, in the county of 5 Essex and State of New Jersey, have invented certain new and useful Improvements in Radiotransmitters, of which the following is a full, clear, concise, and exact description.

10 The present invention relates to high voltage transmission and particularly to high voltage radio transmission.

In radio transmitters for long distance transmission it is not uncommon for the 15 high frequency energy developed in the antenna to amount to several kilowatts. The capacity and inductance of an antenna are generally of such an order of magnitude that the voltages developed at this energy 20 are very high and may frequently amount to 50,000 volts or more.

In any practical system it is desirable to 25 change the connections of the circuits associated with the oscillation circuit for shifting the wave length, varying the coupling, or otherwise adjusting the set of different conditions. If these changes are made during operation of the set, as is frequently desirable or necessary, switching arrangements 30 must be provided which will not only effect the required circuit changes but which will operate at the high voltages present in the circuit.

It is an object of the invention to effect 35 circuit changes in a high voltage oscillation circuit with ease and with safety, and in an efficient manner.

The various auxiliary objects and the different features of the invention will be clear 40 from the following detailed description in connection with the accompanying drawing, in which Fig. 1 shows a plan view, partly in section, of the switching structure of the invention; and Fig. 2 is a schematic representation in simplified form of a type of circuit to which the switching means is applicable.

Briefly and specifically, the invention provides a plurality of switches mechanically 45 connected so as to be actuated from a common wheel or lever. In the case of each switch, a switch arm is supported on a high voltage insulator which serves to actuate the arm. Preferably, the arm itself is non-conducting but carries at its end a short

bridging member of conducting material which wipes over contacts between which connections are to be made. The mechanical driving connection between the separate switches is grounded at a plurality of points 60 to prevent the development of high voltages in it with consequent heating. Contact is made only to the centers of the terminal contacts which are of relatively large surface and are of the proper curvature to relieve 65 the strain on the insulators. The entire structure is enclosed within a grounded shield.

It will aid in the description of the various features illustrated in Fig. 1 to refer 70 first to the circuit diagram of Fig. 2. In this latter figure the antenna circuit comprises the aerial 1, the inductance 2, and one or more of the capacities 3, which may be connected into the circuit as desired. As is 75 well known the aerial has capacity to ground so that the circuit 1, 2, 3, ground, comprises an oscillation circuit. Energy is supplied to this oscillation circuit from the vacuum tube 4 which has its cathode connected to ground and its anode and grid connected to different points on the inductance 2. This manner of connection is commonly known as the Colpitt's type of connection. 80

In this type of connection it is necessary or desirable in a practical installation to vary the point of connection of the aerial 1 to the inductance 2 and also to vary the points of connection of the anode and grid 85 of the tube 4 to the inductance 2 and to connect different ones of the capacities 3 into the circuit. These changes control both the natural period of the antenna circuit and the coupling between the tube 4 and the antenna circuit. This general arrangement of circuit and means for effecting the circuit changes are disclosed in U. S. patent to Clement 90

1,395,390, dated November 1, 1921, to which reference may be made for a fuller disclosure of the purpose and effect of the circuit changes, the present invention having to do with the arrangement for producing these circuit changes in an installation utilizing high power and in which very high voltages 95 exist between points in the circuit.

The switching arrangements with which the invention is particularly concerned are those diagrammatically indicated, in Fig. 2, at 5 and at 6, respectively. 100 105 110

Referring now to Fig. 1 the inductance 2 is shown in the form of a tubing preferably of copper wound on the insulating posts 7 which may be of porcelain or any other suitable material. The switch 5 is shown in this figure below the inductance 2 and the switch 6 is shown to the right of the inductance 2.

For convenience in the description the switch 5 will be designated the inductance-change switch and the switch 6 the capacity-change switch, although this is not to be taken as accurately characterizing the functions which these switches are to perform.

The inductance 2, and the switches 5 and 6 together with the major portion of their driving mechanisms, are enclosed within the metallic casing 8 which is preferably of sheet copper. The condensers, the tube 4 and other portions of the circuit may be contained in the same enclosure or in a separate enclosure. The enclosure or shield 8 is preferably faced by a sheet 9 of micarta or other suitable insulating material.

The control wheel 10, mounted outside of the shield, serves to actuate both switches 5 and 6 through suitable driving mechanism which will be explained hereinafter. The shaft of this wheel extends through the casting and has fixed to it the driving pinion 11 and the high voltage insulator 12. This shaft passes through a bearing member 13 which is provided with a double ball race 14, 15 which permits of easy rotation of the shaft and which acts both as a thrust bearing and as a rotary bearing for the shaft. The bearing member 13 may be enclosed in a suitably fashioned index pointer 16 which is secured to the shaft and is adapted to move over a scale on the front of the panel 9.

Secured to the ends of the insulator 12 opposite the control wheel is a switch arm 17 preferably of micarta and provided with a stiffening rib as shown. This switch arm supports at each end the respective brushes 18 and 19 which upon movement of the wheel 10 are adapted to wipe over the contact ring 20 and a row of contacts 21 arranged in the arc of the circle as shown in Fig. 2.

Each of the contact terminals 21 comprises a metal cap mounted on the end of a high voltage insulator 22. This cap is cup-shaped and suitably curved to relieve undue strain on the insulator 22 due to high voltages existing across it. Connection is made from the individual terminals 21 to desired points in the inductance coil 2, one such connection being indicated at 23. This connection may consist of a copper rod inserted into a hole drilled in the terminal 21, the rod being clamped by a screw or otherwise held fast. The contact ring 20 (which in reality is divided into segments as shown in Fig. 2) is channel shaped and its section resembles

that of the terminal caps 21, the curvature being for the purpose of relieving the high voltage strains, as explained above.

As is seen from Fig. 2 the capacity change switch is located nearer the earth terminal 70 than is the inductance change switch 5 so that the voltages across the terminals of this switch are not as high as those at which switch 5 operates and the insulation can, therefore, be somewhat less. In the case of 75 the switch 6 the switch arm 25 is shown as metallic and is supported by insulators 26 from the sprocket 27. The sprocket is mounted for free rotation on the stub shaft 28 which is secured to the shielding 8. The 80 switch arm 25 carries at one end a brush member 29 which is adapted to sweep over the contact terminals 30 and at its other end carries a single brush 31 adapted to wipe the individual contacts 32. Since lower voltages 85 are dealt with in this switch and lower insulation is required, the leads from contacts 30 and 31 may extend through the insulators as shown. The grid connection is made to a ring 33 mounted on the micarta support 34. 90 Brush 35 secured to the arm 25 makes contact with the ring 33 which is preferably split to prevent affording a closed circuit in which comparatively heavy current may be induced. 95

The sprocket 27 is driven by means of a chain 36 which passes around a sprocket 37 secured to the shaft 38, this shaft being driven by pinion 39 from pinion 11.

It will be noted that the shaft 38 has a bearing near each end secured to the shield 8. The shaft 28 carrying the sprocket 27 is also secured to the shield 8. Since this shield is of highly conducting material and all of the driving mechanism from the pinion 11 to the sprocket 27 is shunted by the shielding, no high voltages are set up in the driving mechanism. If this were not the case, excessive heating might be produced in the driving mechanism which is usually composed of iron or steel. 100 105 110

In operation, the connections from the inductance 2 and the condensers 3 will be brought out to terminals, as explained in Clement's patent, cited, in such manner that corresponding wave length and coupling changes are simultaneously made and that for each new wave length the proper coupling is produced for the best operation of the circuit. The ratios between the pinions 11 and 39 and the sprockets 37 and 27 and also the spacing between the various terminals will be made such that as brushes 18 and 19 are moved from one terminal 21 to the next, corresponding circuit changes 115 120 125 will be effected between the brushes 29 and 31 and their respective terminals 30 and 32. The wheel 10, the casing 8 and the driving mechanism are all at ground potential so that adjustments of the set may be made 130

with safety although it is in the energized condition. Furthermore, the physical connection between the control wheel 10 and the terminals 20 and 21 carrying the highest 5 voltage consists of the insulating bar 17 and the insulator 12 in series.

By providing the relatively short contact members 18 and 19 not only is the insulation between the terminals 20 and 21 and the 10 control wheel 10 increased, but the contact ring 20 can by this manner of construction be divided into segments which are convenient for wiring. The contact members or 15 brushes 18 and 19 preferably bear at only the center portion of the contact members 20 and 21.

I claim:

1. In a wave change switch, a plurality of terminals arranged in an arc of a circle, 20 a contact ring concentric therewith, each terminal comprising a metal cap supported on a separate high-voltage insulator, connections from the caps directly to respective points in an oscillation circuit, said ring 25 being supported on high voltage insulators, a connection from said ring to another circuit, a control post rotatably mounted concentric with said ring and terminals, a bar supported from said control post on a high 30 voltage insulator, and a bridging contact member supported on said bar and adapted to wipe over said contact ring and said terminals.

2. In a wave change switch, an oscillation circuit containing an inductance coil 35 adapted to carry high voltage, a pair of circuits arranged for connection to different points of said coil, a switch for each circuit arranged to change the point of connection 40 between the respective circuit and said coil, a common driving means for both of said switches comprising a metallic mechanical connection between them, and a metallic shield of high conductivity, conductively 45 connected to said driving connection at two points situated near the respective ends of the driving connection to reduce the heating of the driving connection due to its coupling with said oscillation circuit.

60 3. In a high voltage switch, a plurality of

terminals arranged in the arc of a circle, a contact ring concentric therewith, each of said terminals comprising a metal cap mounted on the top of a separate high voltage insulator and being concave on the side 55 next to the insulator and having a smooth curved exterior surface, said contact ring comprising a channel-shaped member with its shortest cross-section concave on the side next to the insulator, and curved on its exterior side, and a bridging contact member having its ends arranged to wipe along the centers of the terminal caps and along the median line of said ring respectively.

4. In a wave change switch, an oscillation 65 circuit having a portion of its elements enclosed in a metallic shield, a pair of circuits adapted for connection to different points in said oscillatory circuit, a pair of switches, each for connecting a different one 70 of said pair of circuits to the oscillatory circuit, said switches comprising each a movable brush arranged to wipe over terminals permanently connected to points in the oscillation circuit, a mechanical driving connection between said brushes and insulated 75 from the brushes, said driving connection being conductively connected to said shield at points near the respective ends of the driving connection.

5. In a wave change switch, an oscillation circuit comprising an inductance, sets of terminals permanently connected to points in said inductance, energizing means for said circuit whereby voltage differences are set up 85 between said sets of terminals of the order of several thousand volts, a movable switch arm for wiping over the terminals of one set, a second movable switch arm for wiping over terminals of another set, common driving 90 means for said switch arms, and means for insulating said switch arms from the common driving means and for preventing overheating of the driving means due to its coupling with the oscillation circuit.

In witness whereof, I hereunto subscribe my name this 21st day of September A. D., 95 1923.

ARTHUR HADDOCK.
